(57) CLAIM

The ornamental design for a toddler shoe, as shown and described.

DESCRIPTION

FIG. 1 is a top perspective view of a toddler shoe, showing my new design;

FIG. 2 is a bottom perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The gray portions surrounded by broken lines are for the purpose of illustrating portions of the toddler shoe that form no part of the claimed design. The broken lines define the boundary of the claimed design and form no part of the claimed design.

1 Claim, 8 Drawing Sheets
